ATTACHMENT PLUG

Lewis J. Clayton, Toronto, Ontario, Canada, assignor to Viceroy Manufacturing Company Limited, Toronto, Ontario, Canada

Application June 20, 1938, Serial No. 214,710

2 Claims. (CL. 173—361)

The principal objects of this invention are to provide an attachment plug of the pronged type which may be manufactured at low cost by a simple moulding operation and in which the 5 prongs will be inserted and flexibly retained in position in an effective manner and in which the lead-in wires may be effectively anchored in a simple manner to the prong terminals.

A further and important object is to provide an 10 attachment plug which will not be injured or broken or rendered otherwise unsuitable for service should the same be trod upon or subjected to shock.

The principal features of the invention reside 15 in the moulded formation of a flattened resilient plug body with terminal receiving sockets and co-operating supporting surfaces and in the provision of pronged terminals specially formed to physically interlock with the walls of the 20 socket and to engage the supporting surfaces in positioning contact.

In the drawing, Figure 1 is a side elevational view partly in section of an attachment plug constructed in accordance with the present invention.

Figure 2 is an edge elevational view.

Figure 3 is a terminal end view.

Figure 4 is a mid-sectional side elevation of the moulded plug body.

Figure 5 is a transverse sectional elevation taken on the line 5—5 of Figure 4.

Figure 6 is an end view of the moulded plug body prior to insertion of the pronged terminals.

Figures 7 and 8 are edge and side elevational views respectively of the insertable pronged terminals illustrating the special formation thereof for co-operation with the plug body.

It is very desirable from a standpoint of service as well as safety to provide an attachment plug 40 for appliances which will be of a resilient nature and not likely to fracture readily and to also provide for the moulding of the plug body separately from the terminals and to provide for the subsequent insertion of the terminals and re-tention thereof in the plug body and while 45 various attempts have been made along this line, difficulty has been experienced either in the assembly of the terminals or the adequate anchoring thereof in the plug body due to inaccurate positioning of the terminals and likelihood of their becoming dislodged from their 50 proper relation to the plug body and the present invention has been devised to overcome these difficulties.

55 In the preferred form of construction shown,

the plug body 1 is moulded from a flexible rubber composition and here shown of flattened tapered form having a central passage 2 which is accessible through a smaller opening 3 either moulded or cut in the convergent end of the 5 body for the reception of the lead-in wires 4.

The inner end face 5 of the plug body is finished in a flat plane and provided with a diagonal slit or slot 6 in register with the central passage 2, forming overhanging lugs 7, the undersides of which are sloped from the respective side walls of the passage 2 diagonally of the axis thereof as indicated at 8 so that when the lead-in wires are inserted through the passage 2 they 10 will be deflected through the slot 6 to be readily 15 grasped.

Pockets 9 lead inwardly from the face 5 on opposite sides of the central passage 2 and the sides of the pockets adjacent the edge of the plug body slope angularly inward from the face 5 20 as indicated at 10 to meet rectangular sockets 11 which extend a substantial depth parallel with the axis of passage 2.

The inner walls 12 of the sockets 11 are provided with socket recesses 13 and one side wall 25 of each of said recesses is raised above the bottom 9' of the pockets 9 and sloped in substantial right angular relation to the respective surface 10 to provide positioning stop abutments 14 hereinafter referred to.

A raised shoulder 15 is positioned at the outward sides of the sloping abutments 14 within the pockets 9 for positioning contact with the edges of the terminals hereinafter referred to.

Upon reference to Figures 7 and 8, the special 35 formation of the insert terminal prongs 16 will be apparent. Each terminal comprises a strip of metal having a prong end 17 and the other end 18 is disposed in a plane parallelly offset from the plane of disposition of the prong 17 40 and the intermediate portion of the metal strip has a part 18' angularly inclined to engage the sloping surface 10 of the plug body in positioning and supporting contact and the adjacent part 17' 45 extends in substantial right-angular relation to the portion 18' so that the undersurface thereof rests in supported positioning contact with the correspondingly sloped stop abutments 14, while the edge portion of the angular part 17' engages the side surface of the adjacent shoulder 15 in 50 positioning contact.

This relationship between the insert terminals and the plug body is achieved when the portions 18 are pressed into the sockets 11 and it will be noted that the portions 18 have a locking 55

lug 18" pressed outwardly therefrom in a wedge-like manner and these lugs embed themselves in the flexible material of the plug body and effectively lock the terminals against accidental withdrawal, but at the same time permit ready insertion of the terminals.

In addition to the supporting contacts above referred to presented by the surfaces 10, 14 and 15, the sides of the overhanging lugs 7 are also surfaced at 7' to engage the flat inner face of the terminals and also at 1" to engage the adjacent edge of the terminals.

The portions 17' have the terminal screws 17''' threaded thereinto and these are of a sufficient length to facilitate the placing of the ends of the lead-in wires thereabout after they have been bent about the edges of the terminals at the ends of the diagonal slot 6. The fact that the terminal screws are angularly related to the terminal prongs 17, provides the desired clearance between the heads of the screws and the prongs to facilitate placing of the wires, while at the same time providing a compact assembly. The inner ends of the terminal screws 17''' are accommodated within the pocket recesses 13.

The resilient nature of the plug body will permit the walls of the slots 6 to be distorted or spread apart to facilitate entry or manipulation of the terminal wires and this may even be made in the form of a slit, so that when the wires are once in position the resiliency of the plug material will retain the slit in its constricted form.

It will be understood however that the invention is not restricted to the use of a rubber composition in the manufacture of the plug body, since other mouldable compositions may be employed while retaining essential features of the invention.

What I claim as my invention is:

1. An attachment plug of the type having a resilient body moulded with terminal-receiving sockets on either side of a central wire terminal passage and terminal prongs inserted in said sockets, characterized in that said body is formed with mating integral wedge-shaped lugs projecting in opposite directions in register with said central passage at one end thereof with their adjacent overlapping edges parallelly tapered to form a slot diagonally intersecting a plane which plane intersects the said terminal prongs centrally and longitudinally, to direct the terminal wires respectively to the opposite outer sides of said terminal-receiving sockets to facilitate connection with the respective terminal prongs. 5

2. An attachment plug of the type comprising a resilient body and terminals recessed into the plug body from one end and presenting prong projections therebeyond, characterized in that said terminals each comprises a single thickness strip of metal bent intermediate of its length to present an obtuse angular portion and a supporting portion therebeyond substantially right-angularly related to the obtuse portion, said latter portion terminating in an anchoring extension obtusely related to said latter portion and offset parallelly from the projecting prong portion, said resilient body being formed to present supporting and positioning contact with said first-mentioned obtuse portions of the terminals and with the inner end of the said projecting prong portions, and a terminal screw threaded into the first-mentioned obtuse portion of each terminal. 20 25 30 35

LEWIS J. CLAYTON.
